HARRISON H. TAYLOR AND JOHN H. WILSON, OF ROCHESTER, NEW YORK.

Letters Patent No. 66,265, dated July 2, 1867.

IMPROVED MACHINE FOR ROLLING STENCH-TRAP PIPE.

The Schedule referred to in these Letters Patent and making part of the same.

TO ALL WHOM IT MAY CONCERN:

Be it known that we, HARRISON H. TAYLOR and JOHN H. WILSON, both of the city of Rochester, in the county of Monroe, and State of New York, have invented certain new and useful Improvements in Machines for Rolling Stench-Trap Pipe; and we do hereby declare that the following is a full and exact description thereof, reference being had to the accompanying drawings, making part of this specification.

Figure 1 is a front view of our machine.

Figure 2 is a side view of the same.

Figure 3 is a detail view.

Figure 4 shows a specimen product of our machine.

Similar letters of reference indicate corresponding parts in all the figures.

The siphon of a stench-trap pipe is usually made in two parts, and these two parts, after being properly shaped, are soldered together. These parts or sections of the siphon have heretofore been formed by being beaten out by hand or by being cast. The object of this invention is to produce a machine by which these sections may be rolled out and made with greater facility than by the ordinary methods, as hereinafter explained.

In the accompanying drawings, A is a grooved roller, and B is a roller having a convex face which runs in the groove of A. These rollers are geared together by the gears I E, fig. 1, and are operated by a hand-crank, D. They are mounted in a frame or stand, C. The upper roller is adjustable, it being suspended in journal-boxes J J, which slide vertically in the frame C, and are held by adjusting-screws k k. B', fig. 3, is a second convex or round-faced roller, and its face is broader than that of roller B. These rollers are used alternately in connection with the grooved roller A, one of them giving the upward turn of the pipe and the other the opposite or downward turn. The rolling face of the roller B, fig. 1, is not concentric with the groove of A, but its greatest diameter approaches nearest to the face of the roller A, so that when one end of the strip of lead, or other material, is introduced between the rollers it is first thrown into a trough shape, and then, as the central parts of the rollers have the least space between them, the bottom of the trough (h, fig. 4) is swaged more than its sides, and consequently the strip or trough is curved and its end H is thrown upward and one of the curves is thereby obtained. The roller B is then removed and is replaced by the second one, B', fig. 3, which is constructed with a wider face than the first roller, so that its greatest swaging action is upon the edges f f, fig. 4, of the strip, and when the opposite end of the strip is run into the machine the swaging action upon its edges bends the end F of the strip or trough in a direction opposite to that of the first part, and by this means these strips of lead, copper, or other suitable material, are readily and rapidly brought into the double-bent form desired, and in the proper shape for soldering. Other forms of the bends may be produced. By these means the construction of these siphons or pipes is greatly facilitated, and an important saving in labor is made, besides which the pipe is much more perfectly and smoothly formed than when cast or beaten out by hand.

Having thus described our invention, what we claim as new, and desire to secure by Letters Patent, is—

The method herein described of forming stench-trap pipe by the employment of the rollers A B B', operating in such a manner as to swage the sides and edges of the pipe unequally, so as to produce the necessary bends, as herein set forth.

In witness whereof we have hereunto signed our names in the presence of two subscribing witnesses.

HARRISON H. TAYLOR,
JOHN H. WILSON.
